UNITED STATES PATENT OFFICE

2,600,053

CHARGING DEVICE FOR KILNS

Arthur Turner Grisenthwaite and George Henry Irons Cruse, Stockton-on-Tees, England, assignors to The Power-Gas Corporation Limited, Stockton-on-Tees, England, a British company

Application August 6, 1947, Serial No. 766,848
In Great Britain January 26, 1940

Section 1, Public Law 690, August 8, 1946
Patent expires January 26, 1960

10. Claims. (Cl. 214—35)

1 The present invention relates to improvements in charging devices for combustion plants such as gas producers, kilns and the like of the type in which a distributor is provided adjacent the inlet opening from a charge chamber.

Charging devices for this purpose are usually provided with three or more separate chutes spaced evenly from one another and symmetrically disposed relatively to a central chute or opening.

It is an object of the present invention to provide a construction whereby the position of the chutes relatively to the upper level of the charge in the kiln may be adjusted.

The invention is further described with reference to the accompanying drawings in which:

Figure 1 is a sectional elevation of one form of construction, the head of the gas producer being shown diagrammatically,

Figure 2 is a corresponding plan view.

The invention will be more particularly described with reference to a gas producer, but a distributor according to the present invention may equally well be applied for the charging of fuel, ore, or other burden to kilns or other apparatus where gas is evolved.

The distributor comprises a number of independent chutes 1, of which eight are shown in the drawings, but it is obvious that three, four, or more can be used as desired, which chutes 1 are preferably closed, that is to say are preferably in the form of tubes or conduits as distinct from open channels, and lead outwardly from a central distributing cone or plate 2 to the outer periphery of the kiln or gas producer, being also symmetrically disposed relatively to one another and to a central opening 3, which may be shrouded by a chute central 4 of truncated form.

The conical plate 2 which receives the burden may conveniently be made detachable, so that it may be renewed when worn.

The whole distributor arrangement 1, 2, 3, 4, is mounted upon a cylindrical or other hollow element 5 carried by three or more rods 6 by which it can be adjusted relatively to the top of the gas producer 7, which producer may be provided in known manner with a water jacket 8 serving for the raising of steam useful in the process of gas manufacture in the gas producer.

It will be seen that, due to the castellated form of the distributor, spaces 9 are provided intermediate the chutes 1, so that the level of the burden within the gas producer can be examined therebetween, and poke rods can be inserted at these places by which the level of the fuel bed

or the like within the producer can be more accurately estimated.

It will be appreciated that by this invention lumps of fuel or other material charged to the producer or kiln, as the case may be, and of differing density or size, will be more evenly distributed over the area of the kiln, and further that the average depth of the bed of material within the kiln will be more nearly approximate 10 to its minimum and maximum depth, whereby steam raising within the jacket 8 will be maintained more constant than has hitherto been possible, and also the fuel bed within the kiln or producer is maintained more constant, so that 15 the gas outlet temperature will also be maintained more uniform.

In use the base of the distributor will lie in contact with the bed of material within the kiln and it is desirable that material be fed from the 20 charging valve 10 in such a manner that some fuel always lies in the lower ends of the chutes 1 and 4.

These chutes may be maintained rigidly in position by stiffeners or ties 12, as shown in Figure 2.

The chutes may also be provided with outlets 11 so that gas derived from the fuel immediately below the chutes may pass out to the gas outlet thus rendering the whole of the fuel bed effective.

We declare that what we claim is:

1. A charging arrangement for furnaces including in combination a central chute, a number of separate spaced segmental chutes disposed around said central chute in one annular row symmetrically peripherally and radially relatively to one another and to said central chute and provided with openings for the passage of gas, rods supporting said separate and 35 central chutes and means to adjust the effective length of said rods to alter the position of the said chutes relatively to the upper level of the charge in the furnace.

2. In a charging device for furnaces, a plurality of chutes within the furnace located at or a little above the normal level of the furnace bed so that fuel delivered to said chutes will be largely initially retained therein and will flow therefrom as combustion in the furnaces proceeds, a charging chamber immediately above said chutes, valve means controlling admission of a charge to said chamber, and means for adjusting the level of said chutes relatively to the furnace.

3. In a charging device for furnaces, a plu-

rality of chutes within the furnace located at or a little above the normal level of the furnace bed so that fuel delivered to said chutes will be largely initially retained therein and will flow therefrom as combustion in the furnaces proceeds, a charging chamber immediately above said chutes, valve means controlling admission of a charge to said chamber, and means to adjust the level of said chutes relatively to the furnace and to restrain rotation of said chutes about a vertical axis.

4. In a charging device for furnaces, a plurality of chutes within the furnace located at or a little above the normal level of the furnace bed so that fuel delivered to said chutes will be largely initially retained therein and will flow therefrom as combustion in the furnaces proceeds, said chutes having one or more apertures therein to enable gas to pass therefrom into the furnace, a charging chamber immediately above said chutes, valve means controlling admission of a charge to said chamber, and means for adjusting the level of said chutes relatively to the furnace.

5. In a charging device for furnaces, a charge receiving chamber, valve means normally closing the upper end of said chamber through which the charge is admitted thereto, a plurality of relatively fixed chutes extending in different directions from the lower part or end of said chamber to direct charged material to parts of the furnace bed, said chutes having one or more apertures therein to enable gas to pass therefrom into the furnace, and means for adjusting the level of said chutes relatively to the furnace bed.

6. A charging device for furnaces comprising upper and lower telescopic elements adapted together to form a charge receiver and of which the lower is adjustable relatively to the upper in an up and down direction, valve means normally closing the upper end of said upper element and through which the charges are fed into said chamber, and a plurality of relatively fixed chutes extending in different directions from the lower end of said lower element for delivering charged material to various parts of the bed in the furnace.

7. A charging device for furnaces comprising upper and lower telescopic elements adapted together to form a charge receiver and of which the lower is adjustable relatively to the upper in an up and down direction, valve means normally closing the upper end of said upper element and through which the charges are fed into said chamber, and a plurality of relatively fixed chutes extending in different directions from the lower end of said lower element for delivering charged material to various parts of the bed in the furnace, said chutes having one or more apertures therein to enable gas to pass therefrom into the furnace.

8. In a charging device for furnaces, a distribution plate within the furnace, a central chute dependent from said plate, a plurality of

separate chutes extending outwardly downwards from said plate, said chutes being located at or a little above the normal level of the furnace bed so that fuel delivered to said chutes will be largely initially retained therein and will flow therefrom as combustion in the furnaces proceeds, said chutes having one or more apertures therein to enable gas to pass therefrom into the furnace, a charging chamber immediately above said chutes, valve means controlling admission of a charge to said chamber, and means for adjusting the level of said chutes relatively to the furnace.

9. In a charging device for furnaces, a charge receiving chamber, valve means normally closing the upper end of said chamber through which the charge is admitted thereto, a central chute dependent from the lower part or end of said chamber, a plurality of relatively fixed separate chutes extending outwardly downwards in different directions from the lower part or end of said chamber to direct charged material to parts of the furnace bed, said separate chutes having one or more apertures therein to enable gas to pass therefrom into the furnace, and means for adjusting the level of said chutes relatively to the furnace bed.

10. A charging device for furnaces comprising upper and lower telescopic elements adapted together to form a charge receiver and of which the lower is adjustable relatively to the upper in an up and down direction but not in a rotary direction, valve means normally closing the upper end of said upper element and through which the charges are fed into said chamber, a distribution plate forming the lower end of said lower element, a central chute dependent from said distribution plate, and a plurality of separate relatively fixed chutes extending outwardly downwards in different directions from said distribution plate for delivering charged material to various parts of the bed in the furnace, said separate chutes having one or more apertures therein to enable gas to pass therefrom into the furnace.
